UNITED STATES PATENT OFFICE

CHARLES HILAIRE HENRI RODANET, OF VERSAILLES, FRANCE, ASSIGNOR TO THE SOCIETY ETABLISSEMENTS ED. JAEGER, OF LEVALLOIS-PERRET, FRANCE

SWITCH

Application filed August 22, 1929, Serial No. 387,760, and in France September 1, 1928.

The present invention has for object improvements in the construction of switches, and more particularly of those arranged at the end of the steering pillars of motor vehicles.

5 The invention first consists in constructing the switch in such a manner that its movable part can have two movements: a movement of rotation and a movement of translation, 10 the movement of rotation being used for the switching of the lighting and luminous signalling circuits, the movement of translation being used for opening or closing the acoustic signalling circuit; then, in actuating 15 this movable part by a rod passing axially through the steering pillar, and terminated by a suitable operating member.

Switches the movable part of which can rotate and move in axial translation are already known, but their application at the 20 end of the steering pillars of motor vehicles is new, and constitutes the main part of the invention. This new application presents this very important advantage that it allows 25 of avoiding the passage of any electric connection through the steering pillar, and all the inconveniences inherent to this faulty arrangement. In fact, through the steering pillar pass only purely mechanical operating 30 members, and preferably a simple rod.

The invention consists also in constructing the switch in such a manner that its fixed part is constituted by a casing made of moulded insulating material, in which all 35 the connections are embedded, the said material leaving only apparent the contact pieces, within the casing, and, at the exterior, the connecting terminals, the current entering through a terminal, the position of which is 40 diametrically opposite that of the terminals of the external circuits. This arrangement considerably diminishes the risks of accidental closing of the circuits.

The invention further consists in providing 45 the casing, on the face which fits against the securing base member, with centering projections also adapted to prevent the casing from rotating and fitting into recesses provided in the said base member; and to 50 mobilize the casing in translation by means

of hooks engaging with a circular ledge on the bottom of the casing. This arrangement allows the builder of the car to place the said hooks in any position which he thinks best.

The accompanying drawings illustrate, by 55 way of example only, a form of carrying out the invention.

Figure 1 is a sectional elevation made according to line A—A of Fig. 2.

Figure 2 is a top plan view corresponding 60 to Fig. 1.

Figure 3 is an underside plan view.

Figure 4 is an underside plan view of the 65 movable part only.

Figure 5 is a top plan view of the fixed 65 part only.

In this example, the fixed part of the switch is constituted by a casing 1, made of moulded material, within which are embedded all the 70 electric connections. Within the casing, the contact pieces 2 only are apparent, these contact pieces cooperating with the contacts of the movable part, as will be explained later on, and, outside the casing, the terminals 3 of the external circuits and the current supply 75 terminal 4 only are apparent. As above stated, the position of the terminal 4 is diametrically opposite that of the terminals 3. In this way, the current supply wire is no longer adjacent to the wires of the external 80 circuit so that the majority of the accidental closings of the circuits is thus avoided.

Within the casing 1 are arranged, in a circle, the contact pieces 2^a corresponding to the contacts for closing the lighting and luminous signalling circuits. In the said casing 1 are also arranged, at the bottom of a central cavity 5, the contact pieces 2^b corresponding to the contacts for closing the acoustic signalling circuit.

The movable part of the switch is constituted by a kind of piston 6 which can either rotate or move in translation within the cylindrical bore of the casing 1. The said piston has an abutting finger 7 extending within a groove 8 provided in the cylindrical edges of the casing 1. The rotation of the piston 6 is thus limited, and it is to be understood that the said finger 7 does not prevent in any way 95 its movement of translation.

The piston 6 is provided with a central rod 9 terminated by a prismatic portion 10 on which is mounted an insulating plate 11, provided with a contact strip 12. The insulating plate 11 is, therefore, rotatively driven by the piston 6. Moreover, the said plate is pushed, by a spring 13, against an abutment 14, which abutment is constituted by two insulating plates 13 and 16 holding a contact 10 ring or crown 17 for the acoustic signalling circuit. A guide rod 18 passes through both insulating plates and the contact ring, then it enters a hole 19 of the piston rod, and is secured, at 20, by riveting, crushing or in 15 any other manner. The guide rod 18 moves in a central hole 21 of the casing.

The piston 6 is provided with a recess 22, in which can enter the flat end of an operating rod axially passing through the steering pillar, and terminated, above the hand wheel, by a suitable operating member.

The operation is as follows:

For actuating the acoustic signal, the driver presses on the operating member; the 25 operating rod, thus actuated in translation, pushes the piston 6. The contact ring 17 then comes in engagement with the two contact pieces 2^a and closes the acoustic signalling circuit. Preferably, as illustrated, the 30 contact ring 17 will be cut out so as to form many slightly bent or curved points, in such a manner as to constitute a multitude of contacts, and ensure, in all circumstances, the positive closing of the signalling circuit.

35 During the movement of translation, the spring 13 has been compressed, so that it suffices for the driver to release the operating member for causing the said spring to automatically break the signalling circuit.

40 For switching the lighting or luminous signalling circuits, the driver causes the operating member to rotate about its axis. The transmission of this rotation to the piston 6 is effected by means of the operating rod passing through the steering pillar and by the flat portion fitted into the recess 22.

The piston 6, by rotating, transmits its movement to the insulating plate 11. The contacts 23, or projections 23 of the contact strip 12, which were in engagement with the contact pieces 2^a of the casing, or with the recesses corresponding to the position of rest in which no circuit is closed, move away from the said contact pieces or recesses by compressing the spring 13. As soon as the said contacts or projections come again opposite other contact pieces 2^a, the spring 13 relaxes, engaging the said contacts with the said contact pieces. In this way, the closing of the 55 circuit and the correct position of the switch are positively ensured.

On its rear face, the casing 1 is provided with a circular recess 24, whereas, on its front face, it is provided with centering projections 65 25. The said centering projections are

adapted to enter corresponding recesses formed in a securing base member belonging to the vehicle, this ensuring the correct angular position of the casing. The latter is fixed in translation by means of hooks 70 engaging with the edge of the circular recess 24, so that these hooks can be arranged in any manner considered as preferable by the builder, without having to modify the casing in any way.

75 The form of construction described is capable of receiving numerous modifications which, reproducing the main features of the invention, some of them or their combinations, are obviously included in the scope of the invention.

80 What I claim as my invention and desire to secure by Letters Patent is:—

1. A switch of the class described comprising a casing having a recess therein, contact strips on the base of the recess, a circular series of contact pieces in the base of the recess, a piston member slidably and rotatably mounted in the recess, a rod fixed to the piston and movable therewith, a plate of insulating material slidably mounted on the rod and rotatable therewith, contact projections carried by the plate for selective engagement with the contact pieces upon rotation of the piston, a guide rod slidably connecting the piston rod and the casing, a contact ring encircling the guide rod and adapted to engage the contact strips upon axial movement of the piston.

95 2. A switch of the class described comprising a casing of insulating material having a recess therein, a piston, a rod for the piston, said piston and rod being slidably and rotatably engaged in the recess, a contact plate 100 slidably and rotatably associated with the piston rod, the base of the recess having contact plates thereon, a contact ring having a plurality of points carried thereby for engagement with the contact strips upon axial movement of the piston, contact pieces in the base of the recess, contact projections carried by the plate for selectively engaging the contact pieces, a spring encircling the rod and having its ends engaged respectively with the plate and piston and a guide rod slidably 105 connecting the piston rod and casing.

110 In testimony whereof I have signed this specification.

CHARLES HILAIRE HENRI RODANET.
